CORNELIUS AULTMAN AND JOSEPH ALLONAS, OF MANSFIELD, OHIO, ASSIGNEES TO
C. AULTMAN AND H. H. TAYLOR, OF SAME PLACE.

Letters Patent No. 92,560, dated July 13, 1869.

IMPROVEMENT IN HORSE-POWERS.

The Schedule referred to in these Letters Patent and making part of the same.

To all whom it may concern:

Be it known that we, CORNELIUS AULTMAN and JOSEPH ALLONAS, both of Mansfield, in the county of Richland, and State of Ohio, have invented certain new and useful Improvements in the Construction of Horse-Powers, of which the following is a full, clear, and exact description, reference being had to the accompanying drawing, and the letters of reference marked thereon, making part of this specification, in which—

Figure 1 is a plan or top view;

Figure 2 is a vertical sectional view through the line *x y*;

Figure 3 is a longitudinal sectional view of the connecting-rod and universal joint, taken at right angles to the view of same devices, as given in fig. 2;

Figure 4 is a vertical sectional view of the upper friction-wheels, and the devices for mounting the same; and

Figure 5 represents a frame-bolster.

Similar letters of reference denote similar parts in all the figures.

The invention relates to that class of horse-powers in which the power is applied to the master or main driving-wheel, by means of horses traversing a circular track, and attached to arms rigidly connected with said master-wheel, the speed of which is multiplied to any desired extent, by means of a system of wheels and pinions, and then transmitted to the thresher, or other machinery, as required.

The invention will be fully understood from the following description.

In the drawing—

A A is the frame, represented as being mounted upon wheels.

B B B are levers secured to the master-wheel C by means of the sockets b b b, this master-wheel being cogged upon its inner diameter.

Supported upon, and firmly secured to the frame A A, is a circular metallic bed-piece, D, and projecting vertically from this bed-piece is a series of studs or spindles, d d d, serving as axles for the spur-wheels E and pinions E, engaging with the master-wheel C.

An intermediate series of spurs or standards d', rising from the bed-piece D, is connected with each other, also with the series marked d, by a rim or disk, D', secured rigidly in place by nuts d' upon the ends of spindles d and standards d'.

The standards d' are shorter than the spindles d, consequently the rim D' assumes an undulating or serpentine form in its course from one to another of these studs; therefore they (the studs d) are supported and braced much more efficiently than they would be if both studs and standards were all of the same height,

and the rim D' occupied, throughout its entire extent, a plane parallel to that occupied by the bed-piece D.

The master-wheel C is provided with a flange, as shown at e, fig. 2, resting upon three or more friction-wheels F, mounted in bearings formed upon or attached to the bed-piece D; and the clamps F', secured to rim D' by nuts d', prevent vertical displacement of the wheel C.

G is a bevel-wheel, mounted upon a spindle rising from an arched transverse bar, extending across the bed-piece.

G' is a pinion attached to bevel-wheel G, and gearing jointly with the three spur-wheels E, thus driving the bevel-wheel G.

H is a pinion-shaft, mounted in suitable bearings in pendent brackets I I, attached to the lower side of bed-piece D.

H' is a bevel-pinion, keyed to shaft H, and driven by bevel-wheel G.

K is an adjustable friction-roller, supported upon one of the standards d', directly above pinion H', and serves to keep the bevel-wheel G in proper relation to the pinion H', thus relieving the spokes or arms of said bevel-wheel from the strain which would otherwise be thrown upon them, by the tendency of the wheel to rise when passing pinion H'. But there is also a tendency in the wheel, at all points in front of this pinion, to rise, the reason for which has been heretofore given, and to counteract this tendency, another friction-wheel, K', is mounted upon another standard, d', at a point as nearly ninety degrees in advance of pinion H' as is practicable.

The manner in which these friction-wheels are mounted is clearly shown in fig. 4, in which d' represents the standard; K, the wheel, supported on a pivot projecting from a wedge-shaped plate, k. The corresponding face k' of the standard d' is also wedging, but in an opposite direction. k' is a bolt, serving to keep the two parts k k' firmly together.

The head of said bolt is confined in a T-shaped groove in standard d', and the relation of parts is such, that an accurate adjustment may be made, and when once made, the wheel K cannot be forced up, except by loosening the bolt k'.

On the outer end of shaft H is a hub, h, expanded in the form of ears, h' h', fig. 3.

L is a sleeve or thimble, provided with a rib, l, made considerably thicker than the rest of the sleeve, to afford a support for the pins h' h', fig. 3. One end of each of these pins is confined in ears h' h', by any suitable device, and the other ends of said pins are confined to opposite sides of the rib l.

The hub N is also expanded into two ears n n, fig. 2, and is connected with rib l by a rod or pivot, n', pass-

ing nearly through said rib, at right angles to the pins h^2 h^3 , and in the same vertical plane, as shown in fig. 3, thus making a universal joint, the halves of which have the axes, about which they vibrate, intersecting each other at right angles.

The rod n^1 has a button-head fitting into a counter-sunk hole in rib l , and the other end of said rod is secured by a latch-string of leather, or an equivalent device, in such manner that it (the rod) does not project beyond the outer surface of the rib l .

The thimble L serves the double purpose of connecting the two parts h and N of the coupling, and also of protecting any substances from becoming entangled with the rapidly-revolving coupling.

M is a tubular sheath, secured at one end to the hub h , and enclosing a torsion connecting-rod, M' , also rigidly fixed in hub h . The other end of rod M' is connected with a hub, N' , and provided with a pointer, n^2 , while the outer end of the sheath is free, and provided with a dial, m , and from the fact that the dial m and pointer n^2 are independent of each other in their movements, they will indicate the amount of tension or twist which is required to be given to the rod M' , in order to move the machinery to which hub N' may be attached.

The torsion-rod is found to greatly relieve both the power and the thresher, or other machinery, from undue strain, in case of sudden variation in the work required of them, as in the case of meeting with obstructions.

The sheath M serves to keep the rod from being deflected or sprung, when strained, and enables us to use a much lighter rod than we could otherwise do.

For the purpose of securing the power in its position upon the ground, we use the following devices:

O O are hounds, hinged to the front axle T , as shown in fig. 1.

O^1 O^2 are transverse bars.

On the front side of bar O^1 is a metallic socket, o , affording a support for the rear end of the tongue, P .

A hammer-strap, o' , secures the whiffletrees.

O^3 is a metallic plate or bracket, connecting the front ends of the hounds, and furnishing a further support for the tongue.

Attached to the rear axle T is a similar pair of hounds, R R , also hinged and united by a metallic bracket.

R^1 R^2 is a bolster, secured to the hounds, and provided with stakes r r , lying in a plane parallel with the hounds R R .

By removing the tongue P , and placing the outer ends of both pairs of hounds upon the ground, and then driving suitable pins or stakes through the holes o^2 r^1 , the frame A A is held in any desired position.

Fig. 5 represents a removable frame-bolster, the posts S S fitting into the metallic sockets s s , on frame A A , and supporting said bolster in a vertical position when required, as will be now explained.

When moving the power from place to place, it is desirable to have a wagon-box to carry tools, &c. In order to construct a box, we place the bolster above described in the sockets s s , then swing up the rear pair of hounds into a vertical position, thus bringing the bolster R^2 on a line with rail S' , in frame-bolster, both of which are high enough above frame A A , so that bottom boards may be laid across from one to the other, without touching the machinery of the power. The hounds are maintained in a vertical position by being connected with bolster S , by means of cleats upon the bottom boards, or in such other manner as may be deemed advisable. The sides of the box are confined by the stakes r r and posts S S , extending above cross-rail S' .

By this arrangement we are enabled to construct a convenient wagon-box, with but little labor, and the employment of no superfluous material.

Having thus described our invention,

What we claim as new, and desire to secure by Letters Patent, is—

1. The combination of the wedge-shaped plate k , the standard d^1 , provided with a wedge-shaped face k' and the bolt k^2 , substantially as and for the purpose set forth.

2. The combination of an elastic or yielding connecting-rod or shaft with the horse-power, for the purpose set forth.

3. The combination of the sheath M with the torsion-rod or shaft M' , for the purpose set forth.

4. The combination, with the universal joint of the driving-shaft, of the removable ribbed thimble L , which serves to connect the two parts of the joint with the pivots intersecting each other, and also to prevent straw and other substances becoming entangled with said joint, as described.

CORNELIUS AULTMAN.
JOSEPH ALLONAS.
